UNITED STATES PATENT OFFICE.

JOSÉ M. RIVERA, OF BUGA, UNITED STATES OF COLOMBIA.

DYNAMO-ELECTRIC MACHINE.

SPECIFICATION forming part of Letters Patent No. 320,170, dated June 16, 1885.

Application filed April 16, 1883. (No model.)

To all whom it may concern:

Be it known that I, José M. RIVERA, of Buga, United States of Colombia, South America, have invented a new and Improved 5 Dynamo-Electric Machine, of which the following is a full, clear, and exact description.

The object of my invention is to provide certain new and useful improvements in dynamo-electric machines, whereby the armature of 10 the same can be rotated without the use of belts or gear-wheels, and a greater or less number of machines can be coupled on one shaft or uncoupled from the same, as may be necessary.

15 A further object of my invention is to facilitate the winding of the armature, and to improve the general construction of the same.

The invention consists in the peculiar construction and arrangement of parts, as herein- 20 after fully described, and pointed out in the claims.

Reference is to be had to the accompanying drawings, forming part of this specification, in 25 which similar letters of reference indicate corresponding parts in all the figures.

Figure 1 is a sectional plan view of my improved dynamo-electric machine. Fig. 2 is a cross-sectional elevation of the same on the line $x x$, Fig. 1. Fig. 3 is an end elevation of 30 the same. Fig. 4 is a cross-sectional elevation of the tubular armature-shaft, and a side view of the spider-wheel on the same. Fig. 5 is a side view of two of the quadrant-sections used in forming the armature-frame. Fig. 6 is 35 a plan view of a series of sections for forming the armature-frame. Fig. 7 is a longitudinal sectional elevation of an armature-frame of a modified construction.

On the driving-shaft A, which is operated 40 by some suitable motor, a tubular shaft, B, is loosely mounted, which shaft is provided with an enlargement, B', forming an oil-chamber for lubricating the sleeve or tubular shaft B on the shaft A.

45 At or near the middle of the tubular shaft or sleeve B a spider-wheel, C, is rigidly mounted on the same, which is preferably provided with four arms, and at the end of each arm with a wedge-shaped lug, C', having a 50 transverse central aperture, a . The ends of the arms of spider C are united by an annular

rim, C'', provided with a series of radial apertures, c , for a purpose which will be described hereinafter.

The armature-frame is composed of a series 55 of quadrant-pieces D, constructed at the ends with large wedge-shaped pieces D' of the same size as the wedge-shaped lugs C'. At the ends of the arms of the spider C and between the end wedge-shaped pieces D' the quadrant pieces D 60 are provided with a series of smaller radial wedges, D'', between which the coils of wire are to be wound. The cylindrical armature-frame consists of four quarter-cylinders, each composed of a series of quadrants, D, held to 65 each other by long rivets E, passed transversely through the several quadrants D between the wedges D''. The ends of the quadrants do not abut against each other, but overlap each other, so that the alternate wedge-shaped pieces D' of 70 the alternate quadrants D overlap each other. Each wedge D' at the end of the quadrants D is provided with an aperture, d , and when the armature-frame is completed the apertures d of the several wedge-shaped pieces D' will coincide with the apertures a of the wedge-shaped lugs C' on the spider-wheel, and long bolts F 75 can be driven through wedge-shaped pieces C', and the several wedge-shaped pieces D' and the nuts on the said bolts can be drawn up 80 tight, whereby the several wedge-shaped pieces D' will be pressed firmly together and will all be held in place on the ends of the arms of the spider-wheel.

The edges of the quarter-cylinders forming 85 the armature-frame will be toothed—that is, the alternate wedge-shaped pieces D' will project beyond the longitudinal edges of the quarter-cylinders, and when the two corresponding quarter-cylinders are placed together the projections on the longitudinal edge of one quarter-cylinder will pass into corresponding recesses in the edge of the other—that is, the wedge-shaped pieces D' will interlock in the same manner that the bricks of brick-work 90 interlock.

The quadrants D are united by the long rivets E; but the armature-frame is held on the spider-frame C by four bolts, F, which pass through the wider or thicker part formed 95 in the armature-frame by the wedge-shaped pieces D', and also pass through the lugs C' of 100

the spider-wheel. The wedges D² form longitudinal grooves in the inner and outer cylindrical surfaces of the armature-frame, and in the said grooves a wire, G, forming the armature-coils, is wound.

The heads H of the field-magnets J are provided with wings H', which overlap the inner or under side of the armature, between the ends of which wings an annular slot is formed, 10 through which the arms of the spider-wheel C can pass. The armature thus revolves in a tubular space between the heads H and their wings H', and thus all sides of the armature will be surrounded by iron. The armature- 15 coil can be wound as one continual coil over the entire length of the armature-frame, or can be constructed with two independent coils, G', which are wound on opposite sides of the spider-frame C. Each half of the armature 20 will then be formed of a series of coils, G', of half the length of the armature-frame, as in Fig. 7.

On the tubular shaft B the commutator K is rigidly mounted, which consists of a series 25 of wedge-shaped metal blocks, L, held on an insulating-sleeve, L', which blocks L are insulated from each other. The connections of the armature-coils are as follows: The inner end of one coil is connected with the outer end 30 of the adjoining coil, and the two united wires are then connected by a wire, g, with one section, L, of the commutator, the said wire g passing through apertures c in the ring C², uniting the ends of the arms of the spider- 35 frame.

The brushes M, resting against the circular surface of the commutator K, are secured to brush-holders N, adapted to slide on insulated segmental plates O, held on the ends of the 40 field-magnet heads, which brush-holders can be locked on the plates O by means of binding-screws O', and thus can be adjusted in the desired position.

On the end of the tubular shaft B a friction-coupling disk, P, is rigidly mounted, which has its outer surface provided with a series of grooves, and a like friction-coupling disk, Q, also provided with grooves, is held to slide on the main driving-shaft A, and is turned or 45 revolved with the said shaft A by a feather or spline, Q', on the said shaft.

The friction-clutch disk Q is provided with a grooved collar, R, into which the forked end of a pivoted lever, S, passes, in which fork 55 the collar can revolve. By means of the said lever S the grooved surface of the clutch-disk Q can be pressed against the grooved surface of the clutch-disk P in such a manner that the two clutch-disks engage with each other, and 60 the rotating disk Q will rotate the disk P and the tubular shaft or sleeve on which the disk P is rigidly mounted, and thereby the spider-wheel C and the armature held on the same will also be revolved.

65 If at any time the movement of the machine is to be stopped, it is only necessary to disengage the clutch-disks P and Q, and if the ma-

chine is to be operated, all that is necessary is to engage the said disks. Thus a number of armatures of machines can be mounted on the 70 shaft A, and any one armature can be coupled to the shaft A by means of the above-described mechanism. One or all of the machines can be operated at will, or can be stopped, so that the quantity of electricity produced can be 75 easily regulated according to the demand.

I call especial attention to the fact that no belts or pulleys are required, and that the mechanism for coupling the machine to the driving-shaft A is very simple and compact, 80 and occupies but very little space.

In order to supply a quantity of fresh air to the armature to prevent the same from being heated, I have provided the wings H', which overlap the under side or inner surface 85 of the cylindrical armature with a series of slots T, through which the air passes to the armature.

The above-described machine can be used as a motor or as an electric generator. The sections forming the armature can be separately detached from each other, thus facilitating the winding of the armature and the replacing of the same. As the spider-wheel carrying the armature-frame is placed in the middle of the 95 same, the rotating parts will be well balanced and will move easily.

Another great advantage of my improved machine is that the wires of the armature are 100 fully protected, and thus are not apt to be injured or covered with dirt or dust.

If two sets of bobbins or coils in the armature are used, one on each side of the spider-wheel, one set can be wound with coarse wire and the other with fine wire entirely independent of each other, so that one set of coils can be used for tension and the other for quantity, in which case the machine would have to be provided with several commutators. As there are to be several machines mounted on 110 the main driving-shaft, some of the machines might be used as motors and the others as current-generators. When there are two separate sets of bobbins on one armature-frame, one set might be used as a motor and the other 115 set might be used as a generator of current—that is, the magnetic field which serves for the motor will be utilized for the generator.

Any machine can be removed from the driving-shaft very easily, and can be replaced by 120 a more or less powerful machine, according as a greater or less number of lights is desired.

I have shown and described the armature-frame constructed of quadrant-pieces; but, if desired, the pieces can be fifths, sixths, or 125 eighths of circles.

Having thus described my invention, I claim as new and desire to secure by Letters Patent—

1. In a dynamo-electric machine, the combination, with an armature, of the spider-wheel to which the center of the armature is fastened, a tubular shaft on which the spider-wheel is rigidly mounted, a driving-shaft passing loosely through the tubular shaft, and a 130

clutch for locking the tubular shaft on the driving-shaft, substantially as herein shown and described, and for the purpose set forth.

2. In a dynamo-electric machine, the combination, with an armature, of a spider-wheel to which the middle of the armature is attached, a tubular shaft on which the spider-wheel is rigidly mounted, which tubular shaft is provided with an enlargement forming an oil-chamber, a driving-shaft passing loosely through the tubular shaft, and devices for locking the tubular shaft on the driving-shaft, substantially as herein shown and described, and for the purpose set forth.

15 3. In a dynamo-electric machine, the combination, with the armature, of the spider-wheel C, attached to the middle of the armature, the tubular shaft B, the driving-shaft A, the clutch-disk P, mounted on the shaft B, the 20 sliding clutch-disk Q, mounted to turn with and slide on the shaft A, and of devices for pressing the disk Q against the disk P, substantially as herein shown and described, and for the purpose set forth.

4. In a dynamo-electric machine, the combination, with the armature, of a field magnet, J, provided with wings H', forming a tubular space in which the armature can revolve, which wings H' are provided with slots or openings T, for admitting air to the armature 30 for preventing overheating of the same, substantially as herein shown and described, and for the purpose set forth.

5. An armature for a dynamo-electric machine, constructed of a series of quadrant-pieces, D, having overlapping wedge-shaped pieces D' at the ends, the rivets E, uniting the several quadrant-sections D, and the bolts F, passed through the apertures d in the said overlapping wedges D', substantially as herein 40 shown and described, and for the purpose set forth.
